UNITED STATES PATENT OFFICE.

HUGH WILLIAMSON KELLY, OF TRENTON, NEW JERSEY, ASSIGNOR OF ONE-HALF TO
AUBREY LOVE, OF RIDGEWOOD, NEW JERSEY.

TRACK-TORPEDO.

1,248,669.

Specification of Letters Patent.

Patented Dec. 4, 1917.

Application filed April 5, 1916. Serial No. 89,075.

To all whom it may concern:

Be it known that I, HUGH WILLIAMSON KELLY, a citizen of the United States, and a resident of Trenton, Mercer county, New Jersey, have invented certain Improvements in Track-Torpedoes, of which the following is a specification.

My invention relates to track torpedoes; and the object of my invention is to provide a torpedo comprising a premolded shell or carrier having a charge of detonating material within the same, which structure may be substantially of the type set forth in my pending applications filed December 3, and 15 24, 1915, Serial Nos. 64,869, and 68,545, respectively, or of other premolded types which may omit the suction means, with rail engaging lugs.

The torpedoes forming the subject of my pending applications comprise shells or holders of rubber, or equivalent material capable of performing the particular function desired and for which rubber is peculiarly adapted; such shells or holders having suction means constituting vacuum cups whereby the torpedo as a whole may be properly secured to the head of a rail. This vacuum cup structure has proved highly efficient in use, excepting in connection with old rails, the tread surface of which may be pitted to such an extent as to preclude the possibility of the complete vacuum necessary to hold the torpedo in place. I propose, therefore, to provide a torpedo of the premolded shell or carrier type, whether having the vacuum cup or not, with additional rail-clasping or clutching lugs of material of the same character as that comprising the torpedo shell and premolded therewith; such lugs being 40 preferably stiffer, that is to say, having less body elasticity, although of substantially the same material as the shell or carrier receiving the mass of detonating material.

These and other features of my invention are more fully described hereinafter, reference being had to the accompanying drawings, in which:

Figure 1, is a cross-sectional view of the head of a rail, showing one embodiment of my improved form of torpedo applied thereto;

Fig. 2, is a side elevation of the torpedo shown in Fig. 1, with the rail-engaging lugs in the position they assume before torpedo is applied to the rail-head;

Fig. 3, is a plan view of the torpedo shown in Fig. 1, in position on the rail-head;

Figs. 4 and 5, are sectional views, similar to Fig. 1, illustrating forms of suction cup structures such as set forth in my pending application filed December 3, 1915, Serial No. 64869, before referred to, with rail-engaging lugs of my present invention;

Fig. 6, is a similar sectional view of a torpedo of the character set forth in my pending application filed December 24, 1915, Serial No. 68545, before referred to, with the rail-engaging lugs of my present invention;

Fig. 7, is a side elevation of a torpedo of a slightly modified shape; being oval or oblong and having the rail-engaging lugs of my present invention, and

Fig. 8, is a plan view of the structure shown in Fig. 7.

The shell or carrier of the torpedo, with or without the "sucker" or vacuum cup which I may employ as the means of securing the torpedo to the head of a rail is preferably made of rubber, although it is obvious that any suitable material of similar characteristics may be employed, and this cup is molded substantially in the shape shown in the several figures, with the integral rail-engaging lugs whereby it may be retained in place, with or without the vacuum cup, when applied to the head of a rail.

Under ordinary circumstances, the "sucker" or vacuum cup structures shown in my pending applications will be sufficient to maintain the torpedo upon the head of a rail. When badly pitted rails are encountered, however, or when rails are partially covered with ice and are undergoing thawing, some difficulty is experienced in maintaining the torpedo upon the rail. It is with a view of overcoming this objection that I propose to secure to or form with the "sucker" or vacuum cup carrier of the detonating material, side projecting lugs or lips which are so shaped and disposed with reference to the torpedo in its engagement with the rail head that they will firmly bite or clutch the latter, being initially constructed with this particular purpose in view.

In Figs. 1, 2 and 3, I have shown a form of shell or carrier 1, premolded into form, having an upper cavity 2 receiving a charge 3 of detonating material, and laterally extending preformed lugs 4 which bite or grip

105

110

the sides of the rail-head 5. The cavity 2 is preferably surrounded by a wall 6 slightly undercut, so as to insure the retention of the detonating material, and the material of the lugs will be relatively stiffer than the body of the shell, though integral therewith. These lugs are so molded or secured to the wall of the shell or carrier that their natural tendency is to bite or clutch the rail-head as shown in Fig. 1; projecting toward each other when the torpedo is not in use, as shown in Fig. 2.

The vacuum-cup structures shown in Figs. 4 and 5, are substantially of the same character as those illustrated in my pending application filed December 3, 1915, Serial No. 64869, to which I have applied the rail-engaging lugs 4^a, which extend from the wall of the shell or carrier in the manner shown. The cup 8 shown in Fig. 4, is somewhat larger than that shown in Fig. 5, and it will be understood that the lugs taper toward their ends, substantially as illustrated in Fig. 3. In Fig. 6, I have shown a vacuum-cup structure of the type illustrated in my pending application filed December 24, 1915, Serial No. 68545, in which the wall of the shell or casing extends over the top of the mass of detonating material. The rail-engaging lugs 4^b will be of the same type as those illustrated with reference to the other views of the drawings.

Various ways of constructing the rail-engaging lugs to insure their clutching tendencies may be employed, and it may, for instance, be desirable to provide the inner surface of the same with elastic means under tension, the normal tendency of which will be to contract the lugs against the opposite sides of the rail-head when the torpedo is applied thereto.

In Figs. 7 and 8, I have shown the improvements constituting the feature of my present invention as applied to a torpedo 45 of a slightly different shape; the shell or carrier being oval or oblong and extending substantially across the rail-head. This structure will omit the vacuum cup but will be provided with the rail-engaging lugs 4^c, which are designed to bite or clutch the rail-head as described with reference to the other structures.

The detonating material may be in the form of a pressed or shaped cake of suitable 55 thickness, weight and dimensions, preferably having a convex upper surface facilitating crushing engagement by the wheel of an engine or train. It will be understood, of course, that the detonating material may 60 be of any suitable shape so long as the shell or carrier with which it is combined is of a practical type. This means, relatively speaking, that when a vacuum-cup structure is employed its rail-contacting portion shall 65 be substantially annular in outline or con-

tour. It will be understood that other forms or packages of the detonating material may be employed; all of which is within the scope of my invention.

It may be desirable to cover the detonating material, and in Figs. 7 and 8 I have shown a covering 10 which may be of any suitable material that will properly engage the shell of the torpedo and be water-proof. The cover shown may be a piece of friction- 75 cloth, tire tape, or the like.

The contacting faces of the rail-engaging lugs may be roughened, as illustrated in Fig. 2, if desired, to enhance their gripping tendencies, and in some instances a tacky 80 adhesive substance may be applied to the lugs, as illustrated in Fig. 7, or in fact to the whole rail-contacting surface of the torpedo, to augment the gripping engagement afforded by the lugs. 85

I claim:

1. The combination with a track torpedo comprising a premolded shell of rubber-containing material and a body of detonating material carried by said shell, of rail-engaging lugs integral with said shell and projecting beyond the sides of the same. 90

2. The combination with a track torpedo comprising a vacuum cup structure and a body of detonating material carried by said vacuum cup structure, of rail-engaging lugs integral with said vacuum cup structure and projecting beyond the sides of the same. 95

3. The combination with a track torpedo comprising a premolded shell structure of rubber containing material with a body of detonating material carried thereby, and flexible rail-head engaging lugs carried by the wall of said shell and provided with tension means designed to cause said lugs to 100 extend toward each other beneath the shell structure and lie in position to clutch or grip the head of a rail. 105

4. The combination with a track torpedo comprising a vacuum cup structure with a body of detonating material carried thereby, and flexible rail-head engaging lugs carried by the wall of said vacuum cup structure and provided with tension means designed to cause said lugs to extend toward each other beneath the vacuum cup and lie in position to grip the head of a rail. 110 115

5. A premolded container for an explosive charge and forming with the latter a track torpedo, comprising a shell of elastic or resilient material and integral rail-engaging lugs carried by said shell. 120

6. A premolded container for an explosive charge and forming with the latter a track torpedo, comprising a shell of elastic or resilient material having a vacuum cup, and integral rail-engaging lugs carried by said shell. 125

7. A premolded container for an explosive charge and forming with the latter a 130

track torpedo, comprising a shell of rubber containing material having a vacuum cup, and integral rail-engaging lugs carried by said shell; said lugs being arranged normally to project toward each other to clutch or grip a rail-head.

8. A premolded container for an explosive charge and forming with the latter a track torpedo, comprising a shell of elastic or resilient material cupped to receive the explosive material, integral rail-engaging

lugs carried by said shell, and a cover for said explosive material.

9. A premolded container for an explosive charge and forming with the latter a track torpedo, comprising a shell of rubber containing material, integral rail-engaging lugs carried by said shell, and means carried by said lugs and designed to cause them to project toward each other to clutch or grip a rail-head.

HUGH WILLIAMSON KELLY.
